CLAIM

The ornamental design for a microfluidic chip, as shown and described.

DESCRIPTION

FIG. 1 is a top front right perspective view of a microfluidic chip showing our new design;

FIG. 2 is a right plan view thereof;

FIG. 3 is a left plan view thereof;

FIG. 4 is a top right perspective view thereof;

FIG. 5 is a top left perspective view thereof;

FIG. 6 is a top front perspective view thereof; and,

FIG. 7 is a bottom rear perspective view thereof.

While the solid lines in the drawings form part of the claimed design, the solid lines provide written description of prospective embodiments that are not claimed when one or more of the solid lines are amended to broken lines.
